PROCESS FOR DECOLORIZING OIL

Filed Oct. 9, 1929

UNITED STATES PATENT OFFICE

1,991,049

PROCESS FOR DECOLORIZING OIL

Sumner E. Campbell, Long Beach, Calif.

Application October 9, 1929, Serial No. 398,533

3 Claims. (Cl. 196—38)

This invention relates to a process for decolorizing oils and is particularly applicable to distillates derived from crude oils, such as petroleum, shale oil, and the like, in the refining thereof.

The principal object of the invention is to provide a process for decolorizing distillates derived from the operation known in the art as "cracking", and hereinafter referred to as "cracked distillates", which distillates will remain stabilized as to color after being subjected to the process and with minimum losses.

A further object is to provide a process in which a minimum quantity of acid is made available to decolorize a maximum quantity of distillate.

A further object is to provide a process by which certain color forming compounds and other impurities are continuously removed from distillates in such form that they may be recovered as by-products of value.

A further object is to provide a process by which gasoline and/or other distillates are decolorized by the use of acid which is continuously used until substantially exhausted in chemical reactions with the distillates and/or impurities therein.

In my co-pending application Serial No. 349,606 filed March 25, 1929 there is disclosed a process in which distillates are decolorized and thereby stabilized as to color by the use of weak acid, or a dilute acid solution, containing, for instance, less than 93.19% H_2SO_4 , or less than concentrated sulphuric acid of 66° Bé. gravity.

By the use of weak acid, through which the distillate is passed, provides for the absorption by chemical reaction of color forming compounds contained in the distillates, such as nitrogenous and other bases, and provides that by the absorption of such bases in the dilute acid up to substantial exhaustion of the acid, the bases may be recovered in the form of by-products of value.

By reference to the drawing, which diagrammatically illustrates a flow sheet of the process, a raw cracked distillate, such as the gasoline fraction of cracked petroleum, is supplied through a feed pipe 10 and valve 26 to a tower 11, comprising the first of a plurality of dilute acid towers 11', 11'', and 11'''.

The plurality of towers 11, 11', 11'', and 11''' are connected in series through valve 27, pipe 14, valve 28, tower 11', valve 27', pipe 14', valve 28', tower 11'', valve 27'', pipe 14'', valve 28'', tower 11''', and valve 27''' to discharge the acid treated gasoline in a continuous stream flow into pipe 15 initially.

The construction and function of each of the

towers are alike and therefore a description of tower 11 will apply to all.

Tower 11 is filled with acid resistant inert material 12, adapted to provide large surface for contacting the distillate with the acid, and each tower is filled partially, to the line X—X, with a dilute acid solution through pipe 13 and valves 37, 37', 37'', and 37''', which acid solution is initially supplied from an exterior source through a valve 13'.

The acid solution may be any dilute acid solution, but preferably a dilute sulphuric acid solution is used as one, for instance, less than 93.19% H_2SO_4 , or about 50% H_2SO_4 . The strength of the dilute acid solution, however, will vary with the nature of the hydrocarbon distillate under treatment to obtain the desired results.

Pipe 15 is divided at a valve 34 to direct the distillate on one side to a valve 33 and a by-pass manifold 32 connected to towers 11, 11', 11'' and 11''' through valves 30, 30', 30'', and 30''' respectively, and on the other side of valve 34 is a withdrawal by-pass manifold 35 which connects the pipe 15 with extensions of pipes 14, 14' and 14'' through valves 31, 31' and 31'' respectively.

The object of the by-passing of the stream flow of distillate around valve 34 is to be able to subject the distillate to acid treatment in the plurality of towers in rotation so that the acid in each tower is substantially exhausted, as will be further described.

A manifold 38 is connected to each tower 11, 11', 11'' and 11''' through valves 29, 29', 29'' and 29''' respectively for passing exhausted acid and reaction products to a storage tank 39 for further treatments.

By continuously flowing a stream of distillate from pipe 10 through the acid towers and connections, as described, to pipe 15, (valves 26', 26'', 26''', 29, 29', 29'', 29''', 30, 30', 30'', 30''', 37, 37', 37'', 37''', 31, 31', 31'' and 33 being closed) the distillate is contacted with successive portions of a dilute acid solution in series relation, to the end that the color forming compounds comprising nitrogenous bases, such as pyridine, quinoline, and the like, and/or other basic impurities, in the distillate are absorbed in decreasing amounts in each tower in proportion as the stream is denuded of such compounds.

The denudation of the basic impurities in the distillate stream by such flow in series causes the dilute acid solution in tower 11 to become substantially exhausted by reaction with such impurities first, while in the last tower 11''' the acid solution will be substantially fresh, the amount

and strength of acid in each tower being regulated to this end.

Upon the substantially complete saturation with impurities of the acid in tower 11, valves 26, 5 27, and 28 are closed and valve 26' is opened to maintain the stream flow through the remaining towers 11', 11'', and 11''' serially.

Valve 29 is now opened to withdraw the exhausted acid and reaction products through pipe 10 38 to tank 39, whereupon valve 29 is closed and valve 37 opened to refill tower 11 with fresh dilute acid solution.

Valves 37 and 34 are then closed and valves 15 33, 30, 27 and 31 opened, whereby tower 11 becomes the last in the series and tower 11' the first in the series.

In this manner the plurality of towers are used in rotation to always provide that the stream of cracked distillate shall be subject first to a partially spent acid solution, and last to a substantially 20 fresh acid solution, whereby substantially all color forming and other basic impurities are removed by such treatment.

Not only does such treatment with a dilute 25 acid solution insure the removal of the desired impurities, but such is in strong contrast to known treatments of distillates for the removal of such impurities by the use of concentrated acid, in which there may be as much as 80% of the original 30 concentrated acid drawn off in the acid sludge with the impurities and which is generally a total loss.

The dilute acid is substantially completely used up and the reaction products are in the form from 35 which by-products of value may be recovered.

The stream of distillate thus treated with dilute acid solution is conveyed through pipe 15 to a settling tank 16, from which any acid carried over is removed through a pipe 17, the rate of throughput being so regulated that a minimum quantity of weak acid is thus carried over.

From tank 16 the distillate passes through a pipe 18 and valve 40 to an alkali tower 19 which has previously been partially filled to the line 45 Y—Y' with a relatively strong alkaline solution, for example, a solution of caustic soda, valves 43 and 49 being closed.

Such solution may be, for instance, a solution containing 30% of sodium hydroxide, or other 50 equivalent alkali, which absorbs the acidic impurities in the acid treated distillate with avidity, to the end that the solution absorbs about an equal volume of acidic impurities, or more, depending on the nature of the hydrocarbon material being treated, before becoming exhausted.

Weaker solutions may be used, as well as solutions of potassium hydroxide, or sodium plumbite, but a strong alkaline solution is advantageous to confine the alkaline treatment to a single passage 60 through the alkaline solution, whereby the maximum amount of acidic impurities may be concentrated therein in comparatively small volume and less frequent renewal of the alkaline solution will be required.

However, for convenience, two or more towers 65 19 and 19' are provided in series, primarily to maintain continuous operation and secondly if it is desired to use dilute alkali solutions. In the latter case, a plurality of alkali towers may be arranged in series relation to be used in rotation as already described for the dilute acid towers.

Tower 19 may thus be connected through pipe 70 21 and valves 41 and 40' to tower 19', likewise 75 partly filled with caustic soda solution, the dis-

tillate passing thence through pipe 42 and valve 41' to a settling tank 22, from which any alkaline compounds carried over may be withdrawn through a pipe 43.

Thus, in operation, the acid treated distillate is passed through a plurality of towers containing 5 relatively strong caustic soda solutions, in the first of which substantially all impurities of an acid nature are absorbed, the second tower, in the use of strong alkali, merely assuring that no acidic 10 compounds remain in the distillate.

The passage of distillate through tower 19 continues until the caustic soda therein becomes substantially completely exhausted by reaction with acidic impurities, which include such compounds 15 as phenols, cresols, and the like, and/or organic compounds such as naphthenic acids and the like, whereupon the stream flow of distillates is continued by closing valves 40 and 41 and opening valve 43.

The caustic solution in tower 19' being substantially fresh, insures the continuous removal of acidic impurities as previously described for tower 19.

Valve 44 is now opened and the exhausted 25 caustic solution and reaction products are removed therethrough to line 45 and storage tank 46, whence they may be withdrawn through pipe 47 and the acidic impurities recovered as by-products of value in many ways.

Valve 44 is now closed and valve 48 opened to partly refill tower 19 with fresh caustic solution through a supply pipe 20 to be ready for use upon exhaustion of the caustic solution in tower 19', at which time valves 43, 40', and 41' are 35 closed and valves 40, 41, and a valve 49 in a bypass line 50 are opened, to permit the recharging of tower 19' with fresh alkali solution.

By the steps of the process thus described, the selective treatment of a stream of distillate is 40 provided to first remove basic impurities, and then remove acidic impurities, in a continuous manner in which the acid and alkali used are substantially completely exhausted, the reaction products and color forming compounds being 45 recoverable as by-products of value.

The nitrogenous bases and other basic impurities removed by the dilute acid treatment and collected in tank 39 may be recovered by a treatment such as is described in United States Patent No. 50, 1,686,136, the strength of the dilute acid solutions employed being such as to convert the basic compounds into sulphates without material polymerization, or without reacting materially on acidic impurities to change, or possibly destroy, 55 such as are desired to be collected in the alkali treatment for recovery as products of value.

Such change, or destruction, may be accomplished by the use of concentrated acid in towers 11, 11', 11'', and 11''' when treating a distillate 60 such as gasoline.

The distillate, after acid and alkali treatments, in settling tank 22 may still contain certain other unsaturated and gum forming constituents which cause turbidity and affect the desired brilliancy 65 of the finished distillate.

The partially treated cracked distillate is therefore transferred through a pipe 51 and valve 52 to an inlet pipe 10a controlled by a valve 55 (which inlet pipe 10a may serve for the introduction for further distillate of the same character or for withdrawal of part of the treated distillate) to be distributed through a series of concentrated acid towers 11a, 11b, 11c, and 11d, arranged in like manner to the series of dilute acid 70, 75, 80, 85, 90, 95, 100, 105, 110, 115, 120, 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 1575, 1580, 1585, 1590, 1595, 1600, 1605, 1610, 1615, 1620, 1625, 1630, 1635, 1640, 1645, 1650, 1655, 1660, 1665, 1670, 1675, 1680, 1685, 1690, 1695, 1700, 1705, 1710, 1715, 1720, 1725, 1730, 1735, 1740, 1745, 1750, 1755, 1760, 1765, 1770, 1775, 1780, 1785, 1790, 1795, 1800, 1805, 1810, 1815, 1820, 1825, 1830, 1835, 1840, 1845, 1850, 1855, 1860, 1865, 1870, 1875, 1880, 1885, 1890, 1895, 1900, 1905, 1910, 1915, 1920, 1925, 1930, 1935, 1940, 1945, 1950, 1955, 1960, 1965, 1970, 1975, 1980, 1985, 1990, 1995, 2000, 2005, 2010, 2015, 2020, 2025, 2030, 2035, 2040, 2045, 2050, 2055, 2060, 2065, 2070, 2075, 2080, 2085, 2090, 2095, 2100, 2105, 2110, 2115, 2120, 2125, 2130, 2135, 2140, 2145, 2150, 2155, 2160, 2165, 2170, 2175, 2180, 2185, 2190, 2195, 2200, 2205, 2210, 2215, 2220, 2225, 2230, 2235, 2240, 2245, 2250, 2255, 2260, 2265, 2270, 2275, 2280, 2285, 2290, 2295, 2300, 2305, 2310, 2315, 2320, 2325, 2330, 2335, 2340, 2345, 2350, 2355, 2360, 2365, 2370, 2375, 2380, 2385, 2390, 2395, 2400, 2405, 2410, 2415, 2420, 2425, 2430, 2435, 2440, 2445, 2450, 2455, 2460, 2465, 2470, 2475, 2480, 2485, 2490, 2495, 2500, 2505, 2510, 2515, 2520, 2525, 2530, 2535, 2540, 2545, 2550, 2555, 2560, 2565, 2570, 2575, 2580, 2585, 2590, 2595, 2600, 2605, 2610, 2615, 2620, 2625, 2630, 2635, 2640, 2645, 2650, 2655, 2660, 2665, 2670, 2675, 2680, 2685, 2690, 2695, 2700, 2705, 2710, 2715, 2720, 2725, 2730, 2735, 2740, 2745, 2750, 2755, 2760, 2765, 2770, 2775, 2780, 2785, 2790, 2795, 2800, 2805, 2810, 2815, 2820, 2825, 2830, 2835, 2840, 2845, 2850, 2855, 2860, 2865, 2870, 2875, 2880, 2885, 2890, 2895, 2900, 2905, 2910, 2915, 2920, 2925, 2930, 2935, 2940, 2945, 2950, 2955, 2960, 2965, 2970, 2975, 2980, 2985, 2990, 2995, 3000, 3005, 3010, 3015, 3020, 3025, 3030, 3035, 3040, 3045, 3050, 3055, 3060, 3065, 3070, 3075, 3080, 3085, 3090, 3095, 3100, 3105, 3110, 3115, 3120, 3125, 3130, 3135, 3140, 3145, 3150, 3155, 3160, 3165, 3170, 3175, 3180, 3185, 3190, 3195, 3200, 3205, 3210, 3215, 3220, 3225, 3230, 3235, 3240, 3245, 3250, 3255, 3260, 3265, 3270, 3275, 3280, 3285, 3290, 3295, 3300, 3305, 3310, 3315, 3320, 3325, 3330, 3335, 3340, 3345, 3350, 3355, 3360, 3365, 3370, 3375, 3380, 3385, 3390, 3395, 3400, 3405, 3410, 3415, 3420, 3425, 3430, 3435, 3440, 3445, 3450, 3455, 3460, 3465, 3470, 3475, 3480, 3485, 3490, 3495, 3500, 3505, 3510, 3515, 3520, 3525, 3530, 3535, 3540, 3545, 3550, 3555, 3560, 3565, 3570, 3575, 3580, 3585, 3590, 3595, 3600, 3605, 3610, 3615, 3620, 3625, 3630, 3635, 3640, 3645, 3650, 3655, 3660, 3665, 3670, 3675, 3680, 3685, 3690, 3695, 3700, 3705, 3710, 3715, 3720, 3725, 3730, 3735, 3740, 3745, 3750, 3755, 3760, 3765, 3770, 3775, 3780, 3785, 3790, 3795, 3800, 3805, 3810, 3815, 3820, 3825, 3830, 3835, 3840, 3845, 3850, 3855, 3860, 3865, 3870, 3875, 3880, 3885, 3890, 3895, 3900, 3905, 3910, 3915, 3920, 3925, 3930, 3935, 3940, 3945, 3950, 3955, 3960, 3965, 3970, 3975, 3980, 3985, 3990, 3995, 4000, 4005, 4010, 4015, 4020, 4025, 4030, 4035, 4040, 4045, 4050, 4055, 4060, 4065, 4070, 4075, 4080, 4085, 4090, 4095, 4100, 4105, 4110, 4115, 4120, 4125, 4130, 4135, 4140, 4145, 4150, 4155, 4160, 4165, 4170, 4175, 4180, 4185, 4190, 4195, 4200, 4205, 4210, 4215, 4220, 4225, 4230, 4235, 4240, 4245, 4250, 4255, 4260, 4265, 4270, 4275, 4280, 4285, 4290, 4295, 4300, 4305, 4310, 4315, 4320, 4325, 4330, 4335, 4340, 4345, 4350, 4355, 4360, 4365, 4370, 4375, 4380, 4385, 4390, 4395, 4400, 4405, 4410, 4415, 4420, 4425, 4430, 4435, 4440, 4445, 4450, 4455, 4460, 4465, 4470, 4475, 4480, 4485, 4490, 7630, 7635, 7640, 7645, 7650, 7655, 7660, 7665, 7670, 7675, 7680, 7685,

towers 11, 11', 11'' and 11''', to be used in rotation whereby the distillate is first contacted with partially spent concentrated acid and lastly with substantially fresh strong acid, to the end that all the strong acid is substantially saturated with impurities, or exhausted.

The concentrated acid preferably used is a concentrated sulphuric acid in the neighborhood of 66° Bé. gravity and, inasmuch as the mode of operation of the concentrated acid towers is like that already described for the dilute acid towers, a description of such involves needless repetition to one skilled in the art.

However, the function of the concentrated acid treatment and the results achieved thereby comprise an important step in my process.

While concentrated acid decolorizes a cracked distillate to the required color, in ordinary acid and alkali treatments of cracked distillate there are large losses in acid and in products comprising valuable gasoline fractions which have been polymerized and further the color of such treated cracked distillate does not remain stable.

Likewise, on treating a distillate primarily with concentrated acid, the oxidizing and other chemical effects thereof may change the basic impurities into compounds which are too complex to recover in appreciable quantities, inasmuch as such compounds are in a form not susceptible of easy recovery.

Presumably, also, certain of the hydrocarbon compounds are oxidized by concentrated acid treatment, forming complex reaction mixtures, and are withdrawn in the body of the partly exhausted concentrated acid, the reason for this being the effect of the heat of reaction resulting from the mixture of concentrated acid and cracked distillate.

The further objects of my invention by the succeeding enumerated steps include the treatment of cracked hydrocarbon with a dilute acid in a plurality of treatments whereby the dilute acid is substantially exhausted, the recovery of by-products from the exhausted dilute acid, the then further treatment of the cracked hydrocarbons with a concentrated acid in a plurality of treatments whereby the concentrated acid is substantially exhausted and the loss of concentrated acid and polymerized valuable fractions is minimized, the treatment of the exhausted concentrated acid to recover valuable by-products and a dilute acid suitable for the initial steps of the process, the final decolorization of the cracked distillate to a color of 30+ on the Saybolt colorimeter, and the stabilization of the color of the cracked distillate.

To these ends the partially decolorized distillate is passed by pipes 51 and 10a through the towers 11a, 11b, 11c, and 11d, having respective temperature control coils, or jackets, 67, 68, 69, and 70, wherein it is subjected to the action of concentrated acid, whereby it is finally cleared of certain remaining chromogenic and unstable substances to gain its color and brilliancy and whereby certain hydrocarbon sulphates are formed by the chemical action of the concentrated acid.

Upon exhaustion of the concentrated acid in any of the towers 11a, 11b, 11c, and 11d, the reaction products are withdrawn through line 38a to a storage tank 39a. The treated distillate passes through pipe 15a to a settling tank 16a or other suitable means of separating acid and distillate, whence any concentrated acid carried over is withdrawn through a pipe 17a.

From settling tank 16a the distillate passes through a pipe 18a to neutralizing tanks 19a and 19b containing a suitable alkaline solution of sufficient strength to take care of any acidity in the distillate and thence through a pipe 42a to a wash tank 56 to which water is supplied through a line 57, whereby any alkali is removed and withdrawn through pipe 58.

The distillate thus purified, decolorized, and brilliant, after removal of water, passes from wash tank 56 through line 59 to a filter 66a and thence to storage or other uses.

The exhausted alkali may be withdrawn from either of the towers 19a or 19b through a line 45a to a storage tank 46a, from which tank it may be taken through a pipe 47a for any desired purpose.

While these novel results are obtained, it must not be overlooked that the waste of strong acid, as normally used, is substantially eliminated, as well as the loss of polymerized valuable fractions.

The process as described is adaptable to a distillate obtained from cracking a straight run gas oil, a cracked gas oil, a cracked fuel oil, or a cracked kerosene, variations in the strength of the acid used being permissible in accordance with the characteristics of the distillate being treated.

The effective results of the strong acid treatment on a cracked distillate are due to the temperature controls exercised by the coils 67, 68, 69, and 70 which convey a cooling, or refrigerating, medium and which may be placed exteriorly or interiorly of towers 11a, 11b, 11c, and 11d respectively.

Such temperature control is effective to maintain the cracked distillate at a desired low temperature by carrying away the exothermic heat of reaction, whereby finally the color of the treated cracked distillate remains stable and the loss of polymerized valuable fractions is minimized.

The temperature to which the cracked distillate in towers 11a, 11b, 11c, and 11d is reduced and held should preferably be below 32° F.

The process herein described is, of course, applicable to mixtures of straight run distillate with cracked distillate, the concentrated acid treatment serving not only to remove chromogenic bodies, but also unsaturated and gum forming compounds.

In this respect the term "substantially exhausted" as applied to concentrated acid, initially of from about 80% to 93.19% H₂SO₄, may include any degree of exhaustion by reaction down to the point where the acid properties of the mixture from tank 39a is zero.

The degree of exhaustion of the concentrated acid will, however, be somewhat governed by the type of compounds removable by reaction therewith, it being readily understood that a concentrated acid, as such, may be substantially exhausted when its strength has been reduced to 50% acid.

In general, however, the concentrated acid used in treating the cracked distillate will be reduced to about 20% acid or less, which is, of course, recovered from the treatment in tank 61 and used as make-up weak acid supplied to the weak acid towers 11, 11', 11'', and 11''', and the concentrated acid treatment is found to materially reduce the sulphur content of the distillate. For instance, I have thus reduced the sulphur content of a cracked distillate from 0.337% to 0.042%.

I claim as my invention:

1. A process for decolorizing oils which comprises: continuously passing a stream of cracked hydrocarbon distillate upwardly in succession through a plurality of zones containing pools of dilute sulphuric acid of a strength sufficient to remove the basic impurities in the distillate but insufficient to remove unsaturated hydrocarbons and until the dilute acid is substantially exhausted successively in each zone, passing the stream out of the last zone through a mass of contact material to provide that substantially no free acid solution is carried from said zone with said stream, then passing said stream through an alkaline solution whereby the acidic impurities in the distillate are removed, then subjecting the stream to an extended passage through zones containing pools of concentrated sulphuric acid at a low temperature whereby said concentrated acid is substantially exhausted in each zone in succession, then through an alkaline solution, recovering the exhausted concentrated acid from each of said zones, and treating said exhausted concentrated acid to recover said dilute acid therefrom.
- 10 2. A process for decolorizing oils which comprises: continuously passing a stream of cracked hydrocarbon distillate upwardly in succession through a plurality of zones containing pools of dilute sulphuric acid of a strength sufficient to remove the basic impurities in the distillate but is sufficient to remove unsaturated hydrocarbons and until the dilute acid is substantially exhausted successively in each zone, passing the stream out of the last zone through a mass of contact material to provide that substantially no free acid solution is carried from said zone with said stream, then passing said stream through an alkaline solution whereby the acidic impurities in the distillate are removed, then subjecting the stream to an extended passage through zones containing pools of concentrated sulphuric acid at a low temperature whereby said concentrated acid is substantially exhausted in each zone in succession, then through an alkaline solution, recovering the exhausted concentrated acid from each of said zones, treating said exhausted concentrated acid to recover a dilute acid therefrom, and returning such dilute acid to said dilute acid zones.

in the distillate are removed, then subjecting the stream to an extended passage through zones containing pools of concentrated sulphuric acid at a low temperature whereby said concentrated acid is substantially exhausted in each zone in succession, then through an alkaline solution, recovering the exhausted concentrated acid from each of said zones, and treating said exhausted concentrated acid to recover said dilute acid therefrom.

15 3. A process for decolorizing oils which comprises: continuously passing a stream of cracked hydrocarbon distillate upwardly in succession through a plurality of zone containing pools of dilute sulphuric acid of a strength sufficient to remove the basic impurities in the distillate but is sufficient to remove unsaturated hydrocarbons and until the dilute acid is substantially exhausted successively in each zone, passing the stream out of the last zone through a mass of 20 contact material to provide that substantially no free acid solution is carried from said zone with said stream, then passing said stream through an alkaline solution whereby the acidic impurities in the distillate are removed, then subjecting the stream to an extended passage through zones containing pools of concentrated sulphuric acid at a low temperature whereby said concentrated acid is substantially exhausted in each zone in succession, then through an alkaline solution, recovering the exhausted concentrated acid from each of said zones, treating said exhausted concentrated acid to recover a dilute acid therefrom, and returning such dilute acid to said dilute acid zones.

30 SUMNER E. CAMPBELL.
